LIQUID DISPENSING BOTTLE

William C. Harris, 1400 Cedar Creek, Racine, Wis.

Filed Dec. 28, 1959, Ser. No. 58,828

Term of patent 14 years

(Cl. D58—8)

Figure 1 is a side elevational view of the liquid dispensing bottle employing my new design.

Figure 2 is a side elevational view thereof with the cap removed.

Figure 3 is a side elevational view of the cap thereof.

Figure 4 is a top view of the cap thereof in removed position.

Figure 5 is a perspective top front view thereof.

Figure 6 is a fragmentary cross-sectional view of the cap thereof.

The characteristic features of my design for the liquid dispensing bottle disclosed reside in the cap portion thereof of having the configurations as shown.

I claim:

The ornamental design for a liquid dispensing bottle, as shown and described.
